UNITED STATES PATENT OFFICE.

WILLIAM SHIPLEY GREY, OF SAN FRANCISCO, CALIFORNIA, ASSIGNOR TO TROY
LAUNDRY MACHINERY CO. LTD., OF CHICAGO, ILLINOIS, A CORPORATION OF
NEW YORK.

IRONING-MACHINE.

1,382,724.

Specification of Letters Patent. Patented June 28, 1921.

Application filed May 14, 1920. Serial No. 381,280.

To all whom it may concern:

Be it known that I, WILLIAM SHIPLEY GREY, a citizen of the United States, residing at San Francisco, in the county of San Francisco and State of California, have invented certain new and useful Improvements in Ironing-Machines, of which the following is a specification.

The present invention relates to ironing machines, and particularly that type of ironing machines in which the goods to be ironed are passed between a cylinder and a roller or rollers, of which the former is usually made of relatively large diameter and provided with means for keeping it up to a high temperature, while the latter is usually of smaller diameter and employed in one or more units coacting with the cylinder and having means for forcing it, or them, toward the cylinder to develop the necessary ironing pressure.

Heretofore it has been customary to clothe the smaller roller or rollers with a material that lends to them the inherent quality of yielding under inequalities in the thickness of the goods, such, for instance, as may be developed by buttons or other attachments carried by the goods; but this clothing involves considerable expense in maintaining it. Moreover, it reduces the coacting roll to the capacity of a mere pressure device, without any ironing effect upon the surface of the goods with which it contacts, besides reducing to a certain extent the ventilation of the goods or the evaporation of their contained moisture under the heat of the main cylinder.

One object of the present invention is to eliminate the clothing from the coacting rolls of an ironing machine, to which end the roll or rolls of such a machine have the surface so dressed that it may bear directly upon the upper surface of the goods and not only develop the necessary ironing pressure but produce an ironing effect over the upper surface of the goods in addition to that which is produced by the main cylinder on the under surface. In order that the coacting roll may compensate for unevenness in the thickness of the goods being ironed at any point without interrupting the ironing effect of the remainder of the roller, the

roller is subdivided into a series of short cylindrical sections supported in operative relation to the main cylinder with freedom to recede therefrom, one independently of the other, but each adapted to maintain ironing pressure under normal conditions.

Another object of the invention is to maintain ventilation of the goods being ironed necessary to permit evaporation of their contained moisture under the heat of the main cylinder, and to this end, the independently yielding cylindrical sections of the roller are spaced apart to leave ventilating ridges between them; and in order that the entire surface of the goods may be treated alike, a duplicate roller of subdivided and spaced apart cylindrical sections is located in position to act upon the goods after they leave the first roller, and has its ironing sections alternated in position with those of the first roller so that they correspond in position with the spaces between the sections of the first roller.

The roller sections may be mounted so that they maintain ironing pressure solely through gravitation; or they may be held under the influence of means that increases their pressure over that which would result from their inherent weight. The roller sections may be guided in their movement to and from the surface of the main cylinder by confining them between a pair of guide rolls located at opposite ends of a diameter of the roller which is perpendicular to the direction of their intended movement; or each roller section may be mounted upon a radius arm or between a pair of radius arms extending from a suitable pivot rod. The sectional coacting rollers may receive their drive solely through friction of the goods being fed by the main cylinder, or they may be positively driven through independent means.

Two embodiments of the invention are shown in the accompanying drawings by way of illustration. In said drawings—

Figure 1 is an end elevation of a known type of cylinder ironing machine in which the coöperating rollers ordinarily employed are substituted by the rollers of the present invention.

Fig. 2 is a plan view of the same.

Fig. 3 is a view similar to Fig. 1 showing a modified method of mounting the coacting rollers and developing independent drive therein and increasing their ironing pressure.

Fig. 4 is a plan view of the arrangement shown in Fig. 3; and

Fig. 5 is a detail view of a pair of radius arms used for mounting a roller section of Figs. 3 and 4.

1 represents the main cylinder, and 2, 2, two coacting rolls arranged in position to successively act upon goods to be ironed thereon. The rollers 2 are subdivided in 15 planes transverse to their axes into a series of short cylindrical sections 2^a which, according to Figs. 1 and 2, are confined between the guide rolls 3 located in suitable position to prevent displacement of the rollers in a direction circumferential to the cylinder 1, and at the same time permitting 20 limited displacement of the rollers from the cylinder in the direction in which they tend to move under unevenness in goods that may 25 be fed through the machine. Inasmuch as the sections 2^a may yield independently, displacement of one from the cylinder 1 will not interrupt the ironing effect of the others. Since these sections have limited spaces de- 30 veloped between them by the bosses 2^b, ventilation of the goods or evaporation of their contained moisture is permitted to take place through the spaces. In order that the entire surface of the goods may be treated 35 alike, the sections of the second roller 2 correspond in position to the spaces between the sections of the first roller, and the spaces between the sections of the second roller correspond to the ironing surfaces of the sec- 40 tions of the first roller, so that in passing under the second roller unfinished zones of the goods receive the ironing treatment, and undried zones are afforded an equal opportunity to give off their moisture.

45 Obviously, the sectional rollers 2 may be multiplied in number if desired.

In the embodiment of the invention shown in Figs. 1 and 2, rotation is imparted to the rollers 2, 2, by the friction of the goods that 50 are being fed through the machine by the main cylinder 1.

If it be desired to positively drive the rollers 2, any suitable arrangement may be employed for this purpose, such, for instance, 55 as the friction drive roll 4 (shown in Figs. 3 and 4) which is keyed upon a shaft 5, to which positive rotation is imparted at a speed commensurate with the rotation of the cylinder 1, as, for instance, through the 60 medium of the belt 6. Also, if it be desired to maintain a more accurate control over the rollers 2, or guide them more positively in their movements to and from the cylinder 1, they may be guided by radius arms 7 piv- 65 oted upon the shaft 5, as suggested in Figs.

3 and 4. In this arrangement the radius arms will enter the spaces between the roll sections 2^a and be connected with said sections through means of pintles 8; and in order that the radius arms may enter into proper relation with the shaft 5, the drive roll 4 will also be sub-divided into short cylindrical sections independently keyed to the shaft 5 and each adapted to overlap two roller sections 2^a, each of which has an axial dimension sufficient to not only cover the space between two sections of the other roller, but partly overlaps said sections.

Finally, if it be desired to increase the ironing pressure of the rollers 2, 2, the radius arm 7 will afford a convenient means for embodying this feature in the machine, as for instance, by providing them with horns 9 projecting in position to receive a spring 10. Spring 10 will act by tension if the horns 9 project below the shaft 5, or by expansion if said horns project upwardly from the shaft 5.

I claim:

1. In an ironing machine, an ironing cylinder, and a roller coacting therewith and subdivided into cylindrical sections, each of which is adapted to independently develop ironing pressure toward the cylinder and to yield independently of the others from the cylinder.

2. In an ironing machine, an ironing cylinder, and a roller coacting therewith and subdivided into cylindrical sections, each of which is adapted to independently develop ironing pressure toward the cylinder and to yield independently of the others from the cylinder; the roller sections being positioned to develop ventilating spaces between adjacent sections.

3. In an ironing machine, a cylinder, a coacting roller subdivided into a plurality of cylindrical sections with ventilating spaces between them, and a second roller coacting with the cylinder and adapted to treat the surface of goods left untreated by the first roller.

4. In an ironing machine, a cylinder, a coacting roller subdivided into a plurality of cylindrical sections with ventilating spaces between them, and a second roller coacting with the cylinder and adapted to treat the surface of goods left untreated by the first roller; said second roller being also subdivided into a series of cylindrical sections.

5. In an ironing machine, a cylinder, a coacting roller subdivided into a plurality of cylindrical sections with ventilating spaces between them, and a second roller coacting with the cylinder and adapted to treat the surface of goods left untreated by the first roller; said second roller being also subdivided into a series of cylindrical sections arranged with spaces between them,

and with their spaces alined in the direction of feed of the goods with the ironing surfaces of the sections of the first roller.

6. In an ironing machine, a cylinder, a 5 coacting roller subdivided into a plurality of cylindrical sections with ventilating spaces between them, and a second roller co-acting with the cylinder and adapted to treat the surface of goods left untreated by 10 the first roller; said second roller being also subdivided into a series of cylindrical sections; the sections of the rollers being independently movable to and from the surface of the cylinder.

15 7. In an ironing machine, an ironing cylinder, and a roller coacting therewith and

subdivided into cylindrical sections, each of which is adapted to independently develop ironing pressure toward the cylinder and to yield independently of the others from the 20 cylinder; means being provided for imparting positive drive to the sections of the roller.

8. In an ironing machine, a coacting roller subdivided into a series of cylindrical sections, and means for imparting pressure to 25 said sections independently one of another to increase ironing pressure developed thereby.

Signed at Chicago, Illinois, this 30th day 30 of April, 1920.

WILLIAM SHIPLEY GREY.
